EVACUATING COUPLING

Menke Drewes, Jr., Highland Park, Ill., assignor, by mesne assignments, to Martin-Marietta Corporation, Chicago, Ill., a corporation of Maryland

Filed June 16, 1961, Ser. No. 117,558

6 Claims. (Cl. 62—268)

The present invention relates generally to evacuating apparatus and more particularly to a coupling for use in evacuating the interior of a hollow, space environment-simulating test body to a pressure corresponding to that existing in outer space.

Currently, there is considerable interest in space vehicles, lunar probes, and interplanetary travel, and in the development of suitable test facilities capable of simulating lunar-space environments. The present inventor's application Serial No. 91,859, filed February 24, 1961, describes a space-simulating facility within which are maintained light, temperature, and pressure conditions corresponding to those existing in outer space. The evacuating coupling of the present invention is used in conjunction with the space-simulating test body described in this prior application, and facilitates a reduction of the pressure in this body to the pressure level in outer space (e.g. 1×10^{-8} mm. Hg.).

Essentially, the subject coupling comprises a housing having inlet means in communication with the interior of the space-simulating body, and outlet means in communication with an evacuating pump. Within the housing are means, subsequently to be described in greater detail, for accumulating gases condensable at the temperature existing within the test body, e.g. 70° to 120° K. Accordingly, although virtually all the gases within the test body are drawn into the coupling, only those gases which are non-condensable under the test conditions are withdrawn from the coupling. Thus the load on the evacuating pump is substantially less than what it would be if it were required to withdraw all the gases from the coupling, and a smaller pump may be utilized.

Other features and advantages are inherent in the structure claimed and disclosed, as will become apparent to those skilled in the art from the following detailed description in conjunction with the accompanying drawings wherein:

FIGURE 1 is a vertical sectional view showing an evacuating coupling constructed in accordance with the present invention;

FIGURE 2 is a sectional view taken along line 2—2 in FIGURE 1.

Referring to the drawings, numeral 11 indicates generally an evacuating coupling constructed in accordance with the present invention. Coupling 11 is in the form of a housing having a first conduit portion or inlet means 14 terminating at a flange 13 secured to another flange 27 surrounding a port 31 in the wall of a hollow space-simulating test body indicated generally at 12. Integral with first conduit portion 14 is a main body portion 15 integral with a second conduit portion or outlet means 16 terminating at a flange 28 secured to a flange 29 on a conduit 30 leading to an evacuating pump (not shown). Within housing main portion 15 is a hollow, disk-shaped, fluid cooled baffle 17, and around the periphery of baffle 17 is an annular opening indicated generally at 18. Located between opening 18 and inlet means 14 is a hollow, doughnut-shaped, fluid-cooled gas-condensing or accumulating element 19. Located between annular opening 18 and outlet means 16 is a second hollow, doughnut-shaped, fluid-cooled condensing element 20.

Baffle 17 and doughnut-shaped elements 19, 20 are cooled with a cryogen such as liquid nitrogen. The tem-

2

peratures of these cryogen-cooled elements and of the interior of the test body 12 are on the order of 70° to 120° K. At these temperatures, gaseous molecules tend to rebound like billiard balls in response to impingement against a surface. When the evacuating pump is operating gas molecules are withdrawn from the interior of test body 12, pass through inlet means 14, strike baffle 17 and are initially deflected back and forth between baffle 17 and doughnut-shaped condensing element 19. Gases such as water vapor, carbon dioxide, and others which are condensable at the temperatures existing in the coupling tend to deposit or accumulate on baffle 17 and doughnut-shaped element 19.

That portion of the gas which does not deposit on these elements eventually is drawn around baffle 17 through the peripheral annular opening 18, whereupon gaseous molecules strike and are deflected by doughnut-shaped element 20, located between annular opening 18 and outlet conduit 16. As the molecules are deflected back and forth between baffle 17 and element 20 that portion of the gas passing through opening 18 which is condensable will tend to deposit on baffle 17 as well as on element 20. The only portion finally withdrawn through outlet conduit 16 is made up almost entirely of non-condensable types, such as hydrogen, helium, neon, and the like. Therefore, only a portion of the gas withdrawn through opening 31 of test body 12 passes through the outlet means 16 of the evacuating coupling. Accordingly, the load on the evacuating pump is substantially less than that required if an evacuating coupling constructed in accordance with the present invention were not interposed between the pump and the test body.

Cryogen is circulated through doughnut-shaped elements 19, 20 by inlet conduits 21, 22 respectively and outlet conduits 23, 24 respectively. Cryogen is circulated through hollow disk-shaped element 17, through inlet conduit 25 and outlet conduit 26.

The foregoing detailed description has been given for clearness of understanding only, and no unnecessary limitations should be understood therefrom, as modifications will be obvious to those skilled in the art.

What is claimed is:

1. An evacuating coupling comprising:
a housing having inlet means for connection to the interior of a body-to-be-evacuated, and outlet means for connection to an evacuating pump;
fluid-cooled baffle means within said housing between said inlet means and said outlet means;
an annular opening around the periphery of said baffle means;
and fluid-cooled condensing and accumulating means on each side of said annular opening and adjacent thereto.
2. A coupling as recited in claim 1 wherein said condensing means comprises:
a first hollow, doughnut-shaped element located between said annular opening and said inlet means;
and a second hollow, doughnut-shaped element located between the annular opening and said outlet means.
3. A coupling as recited in claim 2 and comprising:
means on each of said hollow, doughnut-shaped elements for introducing liquid cryogen thereinto;
and means on each of the doughnut-shaped elements for draining said liquid cryogen therefrom.
4. A coupling as recited in claim 1 wherein said baffle means comprises:
a hollow disc-shaped element;
means for introducing liquid cryogen into said hollow disc-shaped element;
and means for draining said liquid cryogen from the disc-shaped element.

5. A coupling for use in evacuating the interior of a space-simulating hollow body to a pressure corresponding to that existing in outer space, said coupling comprising:

a housing having inlet means for connection to the 5 interior of said body and outlet means for connection to an evacuating pump;
 cryogen-cooled baffle means within said housing between said inlet means and said outlet means;
 an annular opening around the periphery of said baffle 10 means;
 and hollow, doughnut-shaped, cryogen-cooled con-

densing means on each side of said annular opening and adjacent thereto.

6. A coupling as recited in claim 5 wherein said baffle means comprises a hollow, disc-shaped element.
